CHRISTOPHER OFFENHAUSER, OF PHILADELPHIA, PENNSYLVANIA.

MIXER-BLADE.

1,248,153.

Specification of Letters Patent. Patented Nov. 27, 1917.

Application filed October 3, 1916. Serial No. 123,493.

To all whom it may concern:

Be it known that I, CHRISTOPHER OFFENHAUSER, a citizen of the United States, residing in the city and county of Philadelphia, State of Pennsylvania, have invented 5 a new and useful Mixer-Blade; of which the following is a specification.

My present invention comprehends a novel construction and arrangement of a mixer 10 blade wherein novel mechanism is provided to effect the adjustment of the mixer arms.

It further consists of a novel construction of a casing; a novel construction of mixer blades, and novel means to effect the adjustment 15 of said blades so that they can be expanded or contracted in order to vary the width of the path through which they travel.

It further consists of a novel construction of a sectional casing and novel means for 20 locking the parts together in such a manner that the sections of the casing can be readily assembled or taken apart whenever desired.

Other novel features of construction and 25 advantage will hereinafter more clearly appear in the detailed description of my invention.

For the purpose of illustrating my invention, I have shown in the accompanying drawing a typical embodiment of it which is 30 at present preferred by me and which in practice has been found to give satisfactory and reliable results, but it is of course to be understood that this embodiment is typical only and that the various instrumentalities 35 of which my invention consists can be variously arranged and organized and that my invention is not therefore limited to the precise arrangement and organization of these instrumentalities as herein set forth.

40 Figure 1 represents a front elevation of a mixer blade embodying my invention.

Fig. 2 represents a section on line 2—2 of Fig. 1.

Fig. 3 represents a side elevation on an 45 enlarged scale of a portion of my device.

Fig. 4 represents a section on line 4—4 of Fig. 3.

Fig. 5 represents a front elevation of the lower end of the main casing.

50 Fig. 6 represents in side elevation a mixer blade in detached position.

Fig. 7 represents in side elevation the upper end of the lower casing.

Similar numerals of reference indicate 55 corresponding parts in the figures.

Referring to the drawings:

1 designates the main or lower casing which is provided intermediate its ends with a longitudinally extending top 2, thereby forming two members which may be braced 60 by means of a cross-bar 3 secured to such members by fastening devices 4 of any desired or conventional type.

The lower end of the casing 1 is preferably flat, as seen in Fig. 2, and of reduced 65 thickness as indicated at 5, and terminates in a rounded bottom, as at 6, and the side arms 7, the under faces of which form a continuation of the curvature on the bottom of the casing.

70 8 designates the blades, a plurality of which are employed in the present instance, and each of these blades preferably has the same conformation and consist of a curved strip of material 9 having intermediate the 75 ends an outwardly extending arm 10, which at their inner extremities are carried by a pivot pin 11, secured to the lower end of the casing 1. The lower end of each blade has its under face curved, as indicated at 12, such 80 under or outer face then extending at a tangent as at 13 and then curving as at 14 toward the upper end of the blade.

85 15 designate links one end of each of which is pivoted as at 16 to its respective blade 8, and the opposite ends of said links are pivoted at 17 to an adjusting rod 18, which is guided in the casing 1 and which at its upper end is provided with an offset portion 19 which terminates in an eye 20.

90 21 designates a pin which extends into the eye 20 and is connected with an adjusting rod 22 which is guided in a tubular casing or sleeve 23. The upper end of the casing 1 terminates in a U-shaped portion 95 24, which is slotted as at 25 to register with the slots 26 in the lower end of the casing 23 so as to provide for the movement of the pin 21 during the adjustment of the blades. The lower end of the casing 23 has 100 secured thereto in any desired manner a block 27.

28 designates a removable fastening pin which passes transversely through the U-shaped portion 24 of the casing 1, through 105 the block 27 and through the lower end of the casing 23 in order to lock the parts together, and this pin 28 is provided with a deflected arm 29 which is normally locked in position by means of a keeper 30, which 110

consists of a pin having a bent end, said pin passing through the block 27 and the casing 23, and being received in the slots 31 in the upper end of the casing 1 and 5 opening through the rear portion of the U-shaped upper end 24, as will be best understood by reference to Fig. 7 and to Fig. 3. By such means the casing members are detachably connected together.

10 32 designates a cap nut connected with the upper casing 23 and through which the adjusting rod passes, said adjusting rod having its upper end threaded to receive a nut 33 which is shown in the form of a hand 15 wheel, in order that the longitudinal adjustment of the adjusting rod 22 and thereby of the blades may be effected. The casing members may be rotated in any desired manner, and in order to illustrate a means for 20 accomplishing this result, I have shown the upper casing 23 as having fixed thereto a gear 34 by means of a set screw 35. This gear 34 is intergeared in any desired manner with the driving mechanism for the mixing machine, and since such connection is 25 old and well-known in the art, I have deemed it unnecessary to illustrate and describe in detail such connection.

The operation of adjusting the blades and 30 of assembling and taking apart the casing will be readily apparent to those skilled in this art, and is as follows:—

By the proper actuating of the nut 33, the 35 adjusting rods 22 and 18 will be moved inwardly or outwardly and owing to the provision of the links 15 and their connections with the blade 8, such blades will be rocked on their fulcrum, as is apparent.

When it is desired to take apart the 40 device, it is simply necessary to turn the arm 29 in the direction seen in the arrow in Fig. 3, whereupon the pin 28 can be withdrawn. The offset portion 19 of the adjusting rod 18 will then be removed from the pin 21 by 45 springing said offset portion outwardly and the casing sections can then be taken apart by causing their relative rotation sufficiently to cause the pin 30 to move out of the curved slot 31, whereupon by relative longitudinal 50 movement of the casing sections, the lower casing section can be removed.

It will now be apparent that I have devised a novel and useful construction of a mixer blade, which embodies the features of 55 advantage enumerated as desirable in the statement of the invention and the above description, and while I have, in the present instance, shown and described a preferred embodiment thereof which will give in practice satisfactory and reliable results, it is 60 to be understood that the same is susceptible of modification in various particulars without departing from the spirit or scope of the invention or sacrificing any of its advantages.

Having thus described my invention, what I claim as new and desire to secure by Letters Patent, is:—

1. A mixer blade, comprising a rotatable casing having a curved bottom face, curved 70 blades having their lower ends pivoted to the casing, links pivoted to said blades intermediate their ends, a rod guided by the casing and movably connected with said links, and means to longitudinally move said rod 75 to cause the upper ends of said blades to move toward or away from said casing.

2. A mixer blade, comprising a rotatable casing having its bottom face curved, blades 80 consisting of curved members pivoted to said casing to cause their lower portions to travel within a circle formed by a radius equal to the radius forming the curvature of said casing bottom face, and an adjusting member guided by the casing and operatively connected with said blades to effect 85 their relative expansion or contraction.

3. A mixer blade, comprising a casing, 90 blades having their lower ends pivoted to said casing, links pivoted to said blades intermediate their ends, a rod guided by said casing and movably connected with said links, a second rod connected with said first rod, and longitudinally adjustable, and means to rotate said casing. 95

4. A mixer blade, comprising a slotted casing having its inner end rounded and having its rear end forming a U-shaped extension, blades pivoted to said casing, links pivotally connected to said blade, a rod 100 longitudinally adjustable in said slot and connected with said links, a driven casing, an adjusting member therein connected with said rod, and means to interlock said casing.

5. A mixer blade, comprising a lower casing, mixing members carried thereby, a blade carried by said lower casing and operatively connected with said mixing members to vary the width of the path through which they move, an upper casing detachably connected with said lower casing, an adjusting member within said upper casing and connected with said rod, means to actuate said adjusting member, and a gear carried by said upper casing to effect its rotation. 110

6. A mixer blade, comprising a lower casing having its inner end rounded and having its outer end substantially U-shape, an upper casing having its lower end adapted to enter the U-shaped portion of the lower casing, 120 said U-shaped portion having a slot therethrough, a pin fixed to said upper casing and adapted to enter said slot, a second pin adapted to pass through said casing and interlock with said first pin, blades carried by 125 said lower casing, a rod operatively connected with said blades and guided in said lower casing, a rod longitudinally adjustable in said upper casing and connected with said first rod, an adjusting screw engaging 130

said second rod and bearing against the upper casing, and driving means operatively connected with said upper casing.

7. A mixer blade, comprising a lower casing having its inner end rounded and provided with curved arms, curved blades having intermediate their ends arms pivoted to said casing, the outer lower face of an arm being curved, then extending at a tangent and then merging into a curved face toward the upper end of a blade, links pivoted to said blades, a rod guided in said lower casing and pivoted to said links, an upper casing having its lower end received in said lower casing, and means to lock said casings together.

8. A mixer blade, comprising a supporting member, blades mounted on opposite sides of said member to have their lower

ends travel inwardly of the forward end of 20 said member when such blades are expanded or contracted, each blade having at all times a portion of its outer face substantially flush with the outer face of said member, and means to expand and contract said blades. 25

9. A mixer blade, comprising a supporting member, blades pivoted at the forward end of said member, each blade having at all times a portion of its outer face substantially flush with the outer face of said member, and means to effect the expansion and contraction of the upper portions of said blades without causing their outer portions to extend longitudinally beyond said member. 30

CHRISTOPHER OFFENHAUSER.
